UNITED STATES PATENT OFFICE.

CHARLES ADAMS-RANDALL, OF NEW YORK, N. Y., ASSIGNOR TO RANDALL AND CAREY VIBRAL-MASSAGE MACHINE COMPANY, A CORPORATION OF NEW YORK.

ELECTROMECHANICAL VIBRATORY MASSAGE APPARATUS.

SPECIFICATION forming part of Letters Patent No. 778,621, dated December 27, 1904.

Application filed January 9, 1904. Serial No. 188,369.

To all whom it may concern:

Be it known that I, CHARLES ADAMS-RANDALL, a citizen of the United States, residing in New York city, in the county of New York and State of New York, have invented new and useful Improvements in Electromechanical Vibratory Massage Apparatus, of which the following is a specification.

This invention relates to electromechanical vibratory massage apparatus, and has for its object to produce a simple and portable electromechanical apparatus for applying vibratory massage to the human body to stimulate the action of the blood and create an excitation of the skin and muscles and for the treatment of muscular, nervous, and other diseases generally.

To these ends my invention consists in the features and in the construction, combination, and arrangement of parts hereinafter described, and particularly pointed out in the claims following the description, reference being had to the accompanying drawings, forming a part of this specification, wherein—

25 Figure 1 is a sectional elevation illustrating one form of my invention. Fig. 2 is a similar view taken at right angles to Fig. 1. Fig. 3 is a detail sectional view illustrating a modification. Fig. 4 is a detail view illustrating another modification. Fig. 5 is a partially diagrammatic and partially sectional view illustrating a still further modification. Fig. 6 is a detail view, partially in section, illustrating another modification. Figs. 7 and 8 are views 35 illustrating a still further modification, and Fig. 9 is a detail sectional view illustrating a slightly-modified construction of the hammer and presser-foot.

Referring to Figs. 1 and 2 of the drawings, 40 the numeral 1 indicates in a general way an electric motor, the numeral 2 indicating the field thereof, and the numeral 3 is the armature. Mounted on the shaft 4 of the armature is a cam 5, which, as shown in the drawings, is elliptical in shape, or, in other words, is double-ended, so that during each complete rotation of the cam it acts twice. Attached to the frame of the electric motor is a handle

6, by means of which the motor and its attached parts may be moved over the parts of the body to which the treatment is to be applied. To the bottom of the frame of the motor is affixed a plate 7, and attached to said plate is an upright tube 8, in which is arranged a rod 9. The rod 9 at its lower end projects through a suitable aperture formed in the bottom of said tube and at its upper end has fixed thereto a button 10. A pin 11 is fixed in one side of the said button and projects laterally therefrom and extends through a suitable slot 12, formed in one side of the tube 8. Arranged around the rod 9 is a spiral spring 13, one end of which bears against the under side of the button 10, but is unattached thereto, and the other end of which rests against the bottom of the tube 8. A pin 11 operates to limit the vertical movement of the rod 9 and also prevents the rod from turning. Attached to the bottom of the rod 9 in any suitable manner is a cap 14, which in the figures of the drawings alluded to is shown as consisting of a cylindrical piece of metal which is screwed on the lower end of said rod. Adapted to be removably connected to said cap is a hammer comprising a body 15, provided on its periphery with a series of spring-fingers 16 and on its under side with a hammer-head 17, said fingers being arranged to grasp the exterior of the body portion 14, whereby the hammer is held in place by friction. The hammer-head 17 is preferably rounded, as shown, and may be formed of any material most suitable for the purpose. Attached to one side of the under portion 7 of the frame of the apparatus is a depending cylindrical stud 18, and fitted on said stud is a tubular support 19, which has attached to its lower end a presser-foot 20, consisting of a plate which is suitably apertured, as at 21, to permit of the passage therethrough of the hammer 17. Fixed transversely in the stud 18 is a pin 22, which projects through a slot 23, formed vertically in the tubular portion 19 of the support, said pin operating to prevent any lateral movement of the presser-plate, so that the latter will always be held in correct relationship to

the hammer 17. The electric motor will of course be connected by suitable wires with any source of electric energy—such as a battery, for example—or the wires of course may be connected up with an electric-lighting or other electric circuit.

As above described the operation is as follows: The operator holds the apparatus in his hand by grasping the handle 6 and applies the presser-foot 20 to that part of the human body which he wishes to operate upon, and by means of the handle the device may be guided from one portion to another of the body at will. The electric current being completed through the motor, the latter causes the cam 5, fixed upon the armature-shaft, to rotate with great rapidity, and as said cam moves past the button 10 it will operate to violently depress said button, and with it the rod and the hammer carried by the latter. As the low portions of the cam pass the button, the latter together with the hammer, will be elevated by the spring 13. It will be thus seen that during each revolution of the armature-shaft and the cam fixed thereon the rod and its hammer will be depressed twice, and as the motor of course rotates very rapidly there will be a continuous pulsatory movement of the hammer upon the cuticle or muscle or muscles to which the presser-foot may be applied. There will thus be produced a species of hammering effect consisting of a very rapid vibratory or pulsatory movement of the hammer or contact-piece upon the body.

As shown, the hammer 17 projects through the aperture in the presser-foot, and the latter operates to sustain the weight of the apparatus and also serves to absorb the vibrations of the apparatus, which otherwise would be transmitted to the hand of the operator. The vibrations in the machines now employed operate to fatigue the operator; but by means of the presser-foot constructed as described they are almost entirely prevented. The tubular upright 19 in practice will be fitted on the pendent support 18 with sufficient frictional tightness to enable the presser-foot to be held in any position to which it may be adjusted.

Instead of the hammer 17 (shown in Fig. 1 of the drawings) the aperture in the presser-foot 21 may be made much larger and on the foot 21 there may be secured a contact-piece or massage-cup 25, constructed of rubber or any other material suitable for the purpose.

It will be obvious that by detachably securing the contact-pieces, massage-cups, or hammers to their actuating mechanism in the manner described there may be interchangeably used hammers particularly adapted for individual cases—for example, upon the muscles of the limbs of the human body. For the treatment of the face or other ultrasensitive portions of the body it may be necessary to use hammers or contact-pieces that would

be much less violent in their action, and by detachably attaching the hammers or contact-pieces in the manner shown and described it is possible to attach to the apparatus a contact-piece or hammer suitable for the particular purpose in hand.

In Fig. 3 the tubular casing 8 is shown as extending through the bottom 7 of the motor-frame and is provided exteriorly with a collar or flange 26, that is secured to said frame in any suitable manner—as, for example, by screws 27. The reciprocating rod in this arrangement is formed in two separate sections 28 and 29, the coil-spring 30 being attached at its upper ends to the button 10 and at its lower end normally rests lightly and with little or no tension upon a pin 31, extending transversely through the rod 29. The lower end of the rod 29 extends through the bottom of the tubular casing and has attached to its lower end a hammer 32, which projects through the aperture 33 in the foot 34, which in the present instance is shown as being cylindrical and attached to the lower end of the cylindrical casing 8 by means of spring-fingers in the manner before described. In this form of device the hammer normally projects through the tubular presser-foot, the distance it projects therethrough being limited by the pin 31 coming in contact with the lower end of the cylindrical casing. In such normal position the pin 31 is out of contact with the lower end of the coiled spring. The movement, therefore, of the hammer is limited by the pin and the upper part of the hammer coming in contact with the lower end of the cylindrical casing and also by the lower part of the hammer becoming flush with the bottom of the presser-foot as the hammer is pressed in and upward when in contact with the body or other surface with proper pressure. It will be understood, of course, that the button 10 is to be actuated by the cam arrangement shown in Fig. 1 of the drawings, and as the cam rotates the spring is compressed by the downward movement of the button, the tension thereof causing the hammer to be vibrated, which vibrations are communicated to that portion of the body being treated and upon which the hammer may rest. In this arrangement the hammer is detached and independent of the other operative parts and is yieldingly actuated. Also as the upward movement of the hammer is restricted undue pressure cannot be put upon the spring to effect the movement of the cam, and for this reason the presser-foot may be removed and a removable piece of soft-rubber tubing 34 may be placed on the hammer 32, as shown in Fig. 4 of the drawings, for the purpose of communicating a gentle vibratory action upon the face or other sensitive parts of the body that may be sore or inflamed.

In the arrangement shown in Fig. 5 of the drawings the motor is constructed in the form

of the well-known automatic electromagnetic vibrator comprising an electromagnet 35, armature 36, spring contact-piece 37, secured to the armature, and the adjustable contact-screw 38, held in a support 39. The armature is suitably fulcrumed, as at 40, and is provided with a regulating-screw 41 for limiting the movement of the armature. In this arrangement the cylindrical casing 8 projects through the base 7 of the motor, in the manner shown in Fig. 3 of the drawings, and the rod 42 is provided at its upper end with the button 10 and at its lower end with a hammer 43, which is removably attached to a head 44 by spring-fingers 45. As before described with reference to Fig. 3 of the drawings, a presser-foot 46 is made tubular in shape and is detachably connected to the bottom of the cylindrical casing 8 by means of spring-fingers 47. The apparatus is also provided with a handle 6 in the manner before described with reference to Fig. 1 of the drawings. The battery and circuit for operating the motor are preferably arranged as follows: The numeral 48 indicates the battery, divided into three sections *a b c*. One side of the section *c* of the battery is connected by a conductor 49 to the binding-post 50, and leading from the other sides of each of the sections of the battery are wires 51, 52, and 53, which are respectively connected to contacts 54, 55, and 56. Said contacts are adapted to be separately engaged by a switch-lever 57, which is connected by a conductor 58 with the binding-post 59. The circuit is traced as follows: Starting from the battery the current passes to the support 39, screw 38, spring 37, normally in contact with 38, wire 60, through the coils of the magnet, thence by wires 61 and 58 and switch-lever 57 back to the battery. This will set up a rapid vibration of the armature after the well-known manner of a vibrating bell and the armature will be caused to strike a rapid succession of blows on the button 10, and thereby 45 vibrate the hammer. It will be readily apparent that by shifting the switch from one to the other of the contacts 54, 55, or 56 one, two, or three sections of the battery may be thrown into action, according to the energy 50 that it may be desired to apply to the motor.

In Fig. 6 I show a still further modification. In the arrangement shown in said figure instead of employing the vibrating arrangement of parts hereinbefore described and for the 55 purpose of producing frictional massage a friction-wheel 62, formed of any suitable material, is fixed upon the armature-shaft 4 and a presser-foot 63 is attached to the frame of the motor. The friction-wheel protrudes 60 through the aperture formed in the presser-foot, and said presser-foot operates to prevent undue friction upon the person being treated.

In Figs. 7 and 8 I have illustrated a still further modification. In the construction shown

in said figures two or more arms 64 project 65 radially from a hub 65, fixed on the armature-shaft 4 of the motor, and in the outer ends of said arms are formed rests or sockets 66, in which are loosely fitted the stems 67 of hammer-heads 68, pins 69 being fixed in said 70 stems and projecting loosely through slots 70, formed in the arms 64. Fixed on the upper end of the frame of the motor is a laterally-projecting apertured plate 71, and arranged over said plate is a sheet of flexible material, 75 such as vulcanite or the like. As the armature-shaft and the arms 64 rotate the hammers are thrown radially outward by centrifugal action and through the aperture in the presser-foot, said hammer striking against 80 the sheet of vulcanite or other material and through the latter communicating the massage treatment to the body of the patient.

It will be observed that in all of the different forms of apparatus shown and described 85 the different forms of the presser-foot are readily removable and interchangeable for the purpose of adopting the particular form of vibrator best adapted to individual cases and also for the purpose of enabling the parts 90 to be sterilized or disinfected, and the same remarks apply with equal truth to the different forms of hammers, contact-pieces, or massage-cups. The presser being made adjustable serves in a manner to determine the force 95 of the vibratory effects and prevents the vibrator bearing upon the body too forcibly and, as before described, takes the weight of the apparatus off of the hands of the operator and overcomes the vibration usually communicated 100 to the hand and arm of the operator.

Having described my invention, what I claim is—

1. In a massage apparatus, the combination with a casing, of an electric motor contained 105 therein, a massage device carried by the casing and actuated by said motor, and a presser-foot connected to the frame of the motor through which presser-foot the massage device projects, substantially as described. 110

2. In a massage apparatus, the combination with a casing adapted to be held in the hand of the operator, of an electric motor contained within said casing, a massage device carried by the casing and actuated by said motor, and a presser-foot adjustably connected to said 115 casing through which presser-foot the massage device projects, substantially as described.

3. In a massage apparatus, the combination with a casing, of an electric motor contained 120 in the casing, a massage device loosely engaged by the motor, the motor operating to project the said massage device in one direction, and a retractile means within the casing operating to return the massage device in 125 opposition to the movement thereof by the motor.

4. In a massage apparatus, the combination

with a casing, of an electric motor contained therein, a massage device having loose engagement with a part of the motor for reciprocating operation, and a resilient means co-
5 operating with the massage device in opposition to the movement of the latter by the motor.

5. In an electric vibratory massage apparatus, the combination with an electric motor, 10 of a hammer reciprocated thereby in one direction, a spring arranged to reciprocate the hammer in the opposite direction, and a presser-foot through which the hammer is arranged to project, substantially as described.

15 6. In an electric vibratory massage apparatus, the combination with an electric motor, of a hammer reciprocated thereby in one direction, a spring arranged to reciprocate the hammer in an opposite direction, a presser-
20 foot through which the hammer is arranged to project, and means for adjusting the presser-foot relatively to said hammer to regulate the pressure of the hammer on the parts operated on, substantially as described.

25 7. In an electric vibratory massage apparatus, the combination with an electric motor, of a hammer reciprocated thereby in one direction, a spring arranged to reciprocate the hammer in the opposite direction, and a re-
30 movable presser-foot through which the hammer is arranged to project, substantially as described.

8. In an electric vibratory massage apparatus, the combination with an electric motor, 35 of a hammer reciprocated thereby in one direction, a spring arranged to reciprocate the hammer in the opposite direction, and a re-
movable and adjustable presser-foot through

which the hammer is arranged to project, substantially as described.

9. In an electric vibratory massage apparatus, the combination with an electric rotary motor, of a cam fixed on the armature-shaft of the motor, a reciprocating rod arranged to be moved by said cam in one direction, a 45 spring for moving the rod in the opposite direction, and a hammer attached to the free end of said rod, substantially as described.

10. In an electric vibratory massage apparatus, the combination with an electric motor, 50 of a reciprocating rod, a double cam on the armature-shaft for moving said rod in one direction, a spring for moving said rod in the opposite direction, a head on the free end of said rod, a hammer provided with spring-fingers constructed to detachably hold the hammer to said head, substantially as described.

11. In an electric vibratory massage apparatus, the combination with an electric rotary motor, of a cam fixed on the armature-shaft 60 of the motor, a movable contact-piece arranged to be engaged by the cam to move said piece in one direction, a presser-foot, a hammer normally projecting through said foot, and a coiled spring disposed between said 65 contact-piece and hammer, said spring being arranged to depress the hammer, and raise the contact-piece, substantially as and for the purpose specified.

In testimony whereof I have hereunto set 70 my hand in presence of two subscribing witnesses.

CHARLES ADAMS-RANDALL.
